AUTOMATIC FUEL SYSTEM HAVING AUTOMATIC SAFETY SWITCHES

David Samiran, Fairfield, Ohio

Application October 8, 1940, Serial No. 360,299

19 Claims. (Cl. 123—139)

(Granted under the act of March 3, 1883, as amended April 30, 1928; 370 O. G. 757)

The invention described herein may be manufactured and used by or for the Government for governmental purposes, without the payment to me of any royalty thereon.

My present invention relates in general to fuel systems provided with a plurality of separate fuel sources, and more particularly to fuel systems in which the contents of a plurality of fuel containers are automatically connected in predetermined order to a source of fuel consumption such as an airplane engine or the like and wherein automatically operating means for accomplishing such results is operable only when there is a normal operating pressure in the oiling system of the engine.

In a fuel system having a selector valve rotated by an electric motor or the like, it is desirable to have the motor respond to fuel pressure failure, so that when such failure occurs as a result of one fuel tank becoming empty the selector valve rotates to the next tank. However, when the engine is stopped, the fuel pump, which is usually engine driven, is also stopped and thereafter fuel pressure falls, so that a fuel pressure responsive switch for operating the selector valve assumes its position indicating fuel failure and causes an undesired operation of the selector valve either at the time the engine stops if the ignition is still turned on, or subsequently at the time the engine is again started and before it has come up to speed so as to operate the fuel pump at a velocity necessary to indicate full operating pressure of the fuel and thereby setting the fuel pressure responsive switch at its normal inoperative position.

To overcome the undesired operation of the selector valve referred to in the preceding paragraph, the purpose of my present invention is to provide an oil pressure responsive switch so connected in the circuit of the fuel pressure responsive switch that current will be supplied to the fuel pressure responsive switch only after the engine has operated the fuel pump sufficiently to build up a fuel pressure that will maintain the pressure responsive switch in its inoperative position.

One object of my invention is to provide such a fuel pressure operated safety switch, which is comparatively simple in construction and simple to connect into the electrical and pressure oiling systems of an airplane engine or the like, and which will prevent any undesired operation of the selector valve because the oil pressure operated safety switch closes only after the pressure in the oiling system has exceeded a predetermined degree.

A further object is to provide a safety switch of the character herein disclosed which is so connected with relation to an indicator light in the automatic fuel system that the indicator light

will indicate to the pilot a closed condition of the ignition switch, so that he can turn it off when leaving the airplane and thereby avoid running down the battery as a result of negligence in turning off the ignition switch in cases where the engine stops from other causes.

Still a further object is to provide a safety switch which is so constructed that the pilot may manually operate it any time desired for the purpose of making tests either when on the ground or in the air, the switch being further designed so that it will return to automatic operation after manual operation when a subsequent operating cycle commences.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a diagrammatic representation of an automatic fuel system with an automatic safety switch connected therein;

Figure 2 is a diagrammatic view of the fuel pressure responsive switch of my system showing it in a position assumed as a result of fuel pressure failure;

Figure 3 is a sectional view through a portion of a clutch and solenoid mechanism of my fuel system;

Figure 4 is a plan elevation of a safety switch thereof;

Figure 5 is a vertical sectional view of the safety switch taken on the line 5—5 of Figure 4;

Figure 6 is a similar vertical sectional view, the left-hand half of which is taken on the sectional line 6—6 of Figure 5 and the right-hand half of which is taken on the line 6a—6a of Figure 5;

Figure 7 is a view similar to Figure 5 showing the parts in a different position, and

Figure 8 is an enlarged sectional view on the line 8—8 of Figure 7.

On the accompanying drawings I have used the reference characters 1, 2 and 3 to indicate fuel tanks. Three tanks are shown for the purpose of illustration. It is obvious, of course, that a greater or less number may be provided without departing from the spirit of my invention.

The fuel tanks 1, 2 and 3 are illustrated as being hydraulically connected by conduits 4, 5 and 6 to a corresponding number of inlet bosses of a selector valve 7. The selector valve 7 has a rotatable plug provided with a port 8 for hydraulically connecting any one of the pipes 4, 5 and 6 with an outlet pipe 9. A shaft 10 is provided for rotating the valve plug.

The conduit 9 extends to a fuel strainer 12, the outlet of which is connected to the inlet of an engine driven fuel pump 13. The shaft 14 there-

of is connected with an engine indicated generally at E, so as to be driven thereby whenever the engine is in operation. The outlet of the filter 12 is also connected with the inlet of a manually operable wobble pump 15.

The outlet of the pump 13 is connected through a switch pressure regulator 16 to an inlet pipe 17 of an air-vapor eliminator 18. The outlet of the wobble pump 15 is also connected to the inlet pipe 17. The air-vapor eliminator 18 has a connection 19 in the form of a conduit for conveying fuel to a fuel injector 20. The fuel injector includes a pressure relief valve 21 through which fuel in excess of the requirements of the injector 20 is returned through a conduit 22 to the intake of the pipe 13.

The air-vapor eliminator 18 has an air-vapor outlet 23 for discharging air and vapor eliminated from the fuel within the eliminator 18. The air and vapor are returned to one of the tanks, such as 3, thereby permitting any fuel condensing from the vapor to return to the fuel supply. In some types of engine a carburetor would be substituted for the fuel injector 20.

For operating the selector valve 7, I provide a gear 24 which meshes with a pinion 25 suitably journaled for rotation on a sleeve 29a. The sleeve 29a is journaled in a stationary bearing sleeve 30a. The pinion 25 is provided with clutch teeth 25a with which at times a toothed face 26a of a clutch disc 26 is adapted to cooperate. The clutch disc 26 is mounted on a square shaft 27 which is pressed as by a spring 28 in the proper direction for normally disengaging the clutch disc 26 from the clutch teeth of the pinion 25.

The square shaft 27 is slidably and non-rotatably associated with the sleeve 29a. A bevel gear 29 is provided on the sleeve 29a for rotation from a motor M. The motor M has a bevel pinion 30 secured to its shaft and meshing with the bevel gear 29 for this purpose. For engaging the clutch disc 26 with the clutch teeth of the pinion 25, I provide a solenoid 31 in which is slidably mounted a plunger 32. A stem 33 extends from the plunger 32 and is adapted to engage the back of the clutch disc 26. Accordingly, whenever the solenoid 31 is energized, the shaft 27 will be forced in a left hand direction against the tension of the spring 28.

For controlling the motor M, I provide a fuel pressure responsive switch S. The switch S has a bellows chamber 34 in which is mounted a collapsible bellows 35. The bellows 35 collapses against the tension of a spring 36 and thereby actuates a stem 37 in a left hand direction. A conduit 38 extends from the bellows chamber 34 to the switch pressure regulator 16, which regulator furnishes fuel under a substantially constant pressure to the conduit 38 as long as the pump 13 is receiving a predetermined quantity of fuel or fuel in excess of such quantity. When the pump runs out of fuel, then the pressure drops within the bellows chamber 34 so that the spring 36 retracts the stem 37.

The stem 37, whenever the bellows is collapsed by suitable fuel pressure acting within the bellows chamber 34, is adapted to move a switch carriage consisting of a supporting bar 39 and a pair of sliding guide rods 40 in a left hand direction, as in Figure 1. The supporting bar 39 has a pair of ears 41 to which is pivoted a switch arm 42 having a telescoping spring-urged extension 43. The extension 43 carries a metallic roller 44 adapted at times to bridge a pair of contacts 45 and 46, as shown in Figure 2. The

roller 44 and the contacts 45 and 46 are suitably insulated from the remaining parts of the switch.

When the fuel pressure drops within the bellows chamber 34, the switch carriage 39-40 will be moved in a right hand direction by the spring 36, whereupon closure of the circuit across the contacts 45 and 46 is effected, as in Figure 2, by the switch arm 42 engaging a stationary stud 47. Such engagement causes the roller 44 to move outwardly relative to the contacts 45 and 46 and bridge them. The contact 45 has a knife edge to urge retention of the roller in bridging relation to it and the contact 46 when moved to the position of Figure 2.

15 The construction of the switch S is such that mere movement of the carriage from the position thereof in Figure 2 to the position of Figure 1 will not open the circuit through the switch parts 45-44-46. When the switch arm 42 and the switch parts just referred to are in the position of Figure 2, the switch can subsequently be opened by a solenoid 48 having a plunger 49 and a stem 50 connected therewith and terminating in a cam lobe 51. The cam lobe 51 is adapted to move from the dotted position of Figure 2 to the full line position thereof, thereby engaging a companion lobe 52 of the switch arm 42 to swing the switch arm to open circuit position whenever the solenoid 48 is de-energized after the position 20 of Figure 2 has been assumed, and subsequently the carriage 39-40 is carried by a build-up of fuel pressure within the bellows chamber 34 to the position of Figure 1, with the roller 44, however, remaining in the position of Figure 2. Such de-energization of the solenoid permits a spring 35 on the stem 50 to effect the above described circuit opening movement of the stem and thereby of the switch arm 42. On the other hand, whenever the solenoid 48 is energized, the plunger 49 is drawn into the solenoid against the tension of the spring to remove the cam lobe 51 from registry with the cam lobe 52, as shown by the dotted lines in Figure 2.

25 As above stated, the switch S is provided for controlling the motor M. The circuit for this purpose includes a source of current supply such as a battery 54, having one side grounded and the other side connected through an ignition switch 55 with the switch contact 46. The wires in this 30 circuit are indicated at 56 and 57. These wires are connected together at a negative terminal 58 of a terminal panel 59. The ignition switch 55 is the one used for ignition system of the engine on which my fuel system is installed. An ignition wire 60 extends from the ignition switch 55 to the ignition system. I connect the ignition switch 55 in the circuit of my fuel system in this manner so that there can be no undesired operation of the fuel system during a time when the engine is not running, providing of course the 35 pilot properly turns the ignition switch off and thereupon no operation of the fuel system is needed because the engine is idle.

The terminal panel 59 has a control terminal 61 with which the contact 45 of the switch S is connected by a wire 62. From the control terminal 61 a wire 63 leads to an oil pressure responsive switch indicated generally at S'. The switch S' is the safety switch of my present invention and will now be described in detail.

65 A bellows chamber 74 is provided which may be mounted on a panel or similar support 79. Within the chamber 74 a bellows 75 is provided, having its upper end sealed relative to the chamber 70 and having a head on its lower end contacting

with the lower end of a stem 77. A spring 78 resists collapse of the bellows, whereas a pipe 80 is adapted to introduce fluid pressure into the chamber 74 to effect such collapse.

Also mounted on the panel 79 is a toggle switch including a handle 124 having a spring extended element 125 adapted to swing a switch arm 64 about its pivotal mounting on a terminal 78. A second terminal 66 constitutes a contact for closing a circuit when engaged by the switch arm 64. When the lever 124 is swung upwardly, as in Figure 5, the circuit is closed across 64 and 66, and when it is swung downwardly, as in Figure 7, the circuit is open.

For automatically swinging the toggle lever 124, I provide a slide plate 126 having a pair of slots 127 receiving bushings 128. The bushings 128 surround screws 129 which serve to connect a mounting plate 130 for the switch mechanism in position on the panel 79. The sliding plate 126 has an extension 131 surrounding the bellows stem 77 and carrying within it a pair of detents 172. The detents 172 are urged as by springs 173 to engage in a peripheral groove 174 around the stem 77. The resistance offered by the detents 172 against dislocation from the groove 174 is greater than the resistance offered by the toggle lever 124 to movement from one position to another. Accordingly, any time the detents 172 are located in the groove 174 and the stem 77 moves to switch closing or switch opening position, it will close or open the switch, and after such positions are reached (as in Figures 5 and 7, respectively), the stem 77 may overrun relative to the detents, as shown in Figure 8. In these instances, the extension 131 of the sliding plate 126 will engage either a yoke 175 or a head 176 on the bellows chamber 74.

Due to the construction just described, the toggle lever 124 may be swung manually from one of its positions to the other, independent of the automatic movement of the switch responding to the stem 77, as sufficient pressure can be exerted on the toggle lever to overcome the resistance of the detents 172 to movement relative to the groove 174 under the influence of the springs 173. Thus when testing either on the ground or in the air, the pilot may manually close or open the switch S' as desired. When the switch has been closed it will be again opened and returned to automatic operation when the bellows 75 moves to switch opening position after moving to switch closing position following closure of the switch by the pilot. Reversely, the switch will be returned to automatic operation after it is once opened by the pilot.

A wire 65 leads from the contact 66 of the switch S' to a resistance shunting switch having a stationary contact 67 and a movable contact 68. The contact 68 is connected by a wire 69 to one side of the motor M, the other side of which is grounded by a wire 70.

A resistance element 71 shunts the switch 67-68 so that whenever the switch is open the resistance element is in series with the motor M, thereby slowing down its rotation for a purpose which will hereinafter appear. To operate the switch 67-68, I provide a cam disc 72 mounted on the shaft 10 and having cam lobes 72a, 72b and 72c. The lobes are adapted to successively cooperate with a cam lobe 73 of the movable switch contact 68 to lift it from engagement with the stationary contact 67 whenever any of the lobes 72a, 72b or 72c of the cam disc 72 registers with the lobe 73.

The bellows chamber 74 of the switch S' is connected as by the pipe 80 to the oiling system of the engine E. The oiling system is shown diagrammatically as a pump 81 and a gauge 82 showing the pressure.

The solenoid 48 is also controlled by the switch S through a wire 83 connected with the control terminal 81, normally opened switch contacts 84 and 85, a wire 86 and a ground wire 87. Thus although the solenoid 48 is under control of the switch S, it can be energized only when the contacts 84 and 85 are engaged with each other.

The contacts 84 and 85 are controlled by a cam disc 88 having notches 88a, 88b and 88c. The notches are adapted to successively receive a cam lobe 89 of the switch contact 85 to open the circuit across it and the contact 84. Rotation of the shaft 10 on which the cam disc 88 is mounted, to a position other than registry of any of the notches with the lobe 89, results in closure of the circuit for the solenoid 48.

In addition to the resistance 71 being shunted by the switch 67-68, it is also shunted by contacts 90 and 91 of a relay R. The contact 90 is connected by a wire 92 to one end of the resistance element 71, while the contact 91 is connected by a wire 93 to the other end thereof.

The relay R has a coil 94 connected by a wire 95 to the control terminal 81 and by a wire 96 to a three-pole commutator blade 97. The commutator blade 97 coacts with commutator segments 98a, 98b and 98c of a commutator drum 98. Individual blades 102, 103 and 104 are connected by wires 102, 103 and 104, respectively, to float switches 105, 106 and 107. The float switches are located at the fuel tanks 1, 2 and 3, each float switch including a suitable float 108 responsive to the level of fuel in the tank and so connected with the float switch that when the fuel tank is nearly empty, as in the tank 1 of Figure 1, the float switch is nearly closed. The closing of the switch occurs just before the float rests on the bottom of the tank. In this manner, each tank when empty effects closure of its float switch, so that a circuit may be established from either of the wires 102, 103 or 104 to ground wires 109, 110 or 112, respectively, of the float switches 105, 106 and 107.

My fuel system includes an indicator light 113 connected by a wire 114 to the control terminal 81 and by a wire 115 to ground. Thus the indicator light is energized any time that the switch S closes. For testing the indicator light, a manual testing switch 116 is provided connected by wires 117 and 118 between the negative terminal 58 of the control panel 59 and the indicator light.

It is desirable, in an automatically operable selector valve of the character herein disclosed, to permit manual rotation of the valve to any fuel tank or to "off" position. For this purpose I provide a control handle 119 on the selector valve shaft 10 having a pointer 120 cooperating with a dial 121. The dial 121 may be inscribed with "1, 2, 3" and "off," indicating the respective fuel tanks, with any one of which the selector valve may connect, and "off" position indicating that none of them are so connected. The handle 119 may be operated either clockwise or counter-clockwise any time desired, inasmuch as the solenoid 34, normally de-energized, results in the clutch connection 25-26 being inoperative. In the event that the solenoid is energized, the handle 119 can still be rotated as desired, as the

clutch teeth held in engagement by the solenoid can nevertheless ratchet past each other.

Practical operation

Assuming a fuel level in the tank 1 as shown, and that further fuel is then pumped therefrom, the float 108 therein will lower and close the float switch 105. A circuit can now be traced from the ground wire 109 of the float switch 105 through elements 102, 99, 98a, 97, 96, 94, 95 and 82 to the switch contact 45. The switch S, however, is open so that there is no current flow. Accordingly the pump 13 may continue to operate for draining substantially all of the fuel from the tank 1.

When the pump 13 runs out of fuel, it can no longer keep pressure up in the switch pressure regulator 16 and the conduit 38 leading to the bellows chamber 34 of the switch S. Accordingly the spring 36 expands the bellows 35 and moves the switch carriage 39-40 to the right, as in Figure 2, thus closing the switch S. Closure of the switch S energizes the control terminal 61 from the battery 54 through the following elements: 55, 56, 57, 46, 44, 45 and 62. Therefore the relay coil 94 is energized for attracting the armature and thereby closing the contacts 90 and 91. Such closure of the relay contacts produces no result since the resistance element 71 is already shunted out of the motor circuit by the switch 67-68.

Closure of the switch S in addition to energizing the relay circuit just described establishes three other circuits as follows: (1) a circuit for the motor M from the control terminal 61 through elements 63, 78, 64, 66, 65, 67, 68, 69 and 70; (a) a circuit for the solenoid 48 from the control terminal 61 through elements 83, 84, 85, 86 and 87, the solenoid, however, remaining de-energized until the motor M has rotated the shaft 10 sufficiently for the cam notch 88a to pass the lobe 89 and close the contacts 84 and 85. Thereupon the cam lobe 51 of the solenoid 48 will move from the full line position to the dotted position of Figure 2. (3) The clutch solenoid 31 will be energized by current from the control terminal 61 through wires 122 and 123. Thus as soon as the motor M starts to operate the clutch solenoid is energized to electrically connect the motor with the selector valve.

With the solenoids 41 and 38 energized and the motor M operating, the selector valve will rotate from the position of Figure 1, with the port 8 of the valve plug registered with the intake conduit 4, to a position where the port 8 starts to register with the next successive conduit 5. As soon as the segment 98a of the commutator 98 leaves the commutator blade 99, the relay coil 94 will be de-energized, and if the fuel tank 2 contains sufficient fuel to position the float switch 106 in its open circuit position, the relay will not be reenergized when the commutator segment 98b bridges the blades 100 and 97. When the movement of the selector valve has been nearly completed, the next cam lobe 72b will open the switch 67-68, thereby opening the shunt circuit therethrough for the resistance element instead of directly across the closed switch contacts 67 and 68. This effects slowing down of the motor M so that during the completion of the selector valve movement, while the port 8 is being aligned with the conduit 5, there will be slow enough movement to permit the port to stop in exact registry with the conduit as soon as the motor M and the clutch solenoid 31 are de-energized.

During this final aligning movement of the port and conduit of the selector valve, fuel is being picked up from the tank 2 by the pump 13 and thereby pressure is built up within the bellows chamber 34 of the switch S. The switch carriage 39-40 will accordingly be carried from the position of Figure 2 to the position of Figure 1, with the switch 45-44-46, however, still in closed position because the lobe 51 is in the dotted position of Figure 2. Finally, when the port and conduit are in exact registry, the lobe 89 of the switch blade 85 will drop into the notch 88b, thus de-energizing the solenoid 48, causing it to quickly move to the position of Figure 1 for opening the switch S through engagement of the lobe 51 with the lobe 52.

This results in de-energization of the control terminal 61 and subsequent de-energization of the motor M and the clutch solenoid 31. De-energization of the clutch solenoid insures instant stopping of the selector valve without any possibility of overrun as might occur if the selector valve were directly connected with the motor and thereby subject to motor overrun after the motor has been de-energized. At about the same time that the lobe 89 of the switch blade 85 drops into the notch 88b, the lobe 73 of the switch blade 68 drops behind the lobe 72b of the cam disc 72, thus positioning the switch 67-68 for subsequent operation.

The purpose of the automatic safety switch S' responsive to pressure in the oiling system of the engine is to insure that the engine must be started before current is supplied to the circuit of the motor M. This is necessary because the pressure in the fuel supply system, and consequently in the bellows chamber 34 of the switch S at the time of starting of the engine, is too low or in fact is substantially zero, and hence the switch S will be in the closed position of Figure 2, thus starting the motor M. This would result in the selector valve 7 shifting to the next tank, and if the fuel pressure were still low it would shift on to the succeeding tank, even though the tanks were full of fuel. Such operation of the selector valve is unnecessary and is undesirable because, during the shift from one position to the next, i. e., when the port 8 is out of registry with any of the conduits 4, 5 and 6, there would be no fuel supplied to the pump 13.

If the pilot, before starting his engine, would use the wobble pump 15 to create a pressure condition in the fuel system, and in the switch S, then the carriage 39-40 would be moved toward the left from the position in Figure 2 and the cam lobe 51 would be contacted by the cam lobe 52, resulting in opening of the switch S to the position of Figure 1. It is undesirable, however, to impose this task on the pilot in order to insure that the selector valve would remain in adjustment for a given tank until the engine is started. By providing the switch S', however, it is unnecessary for the pilot to operate the wobble pump inasmuch as sufficient pressure to open the switch S can be built up in the fuel system within a period of about one-half minute and the switch S' can be set so that it will not close until expiration of a time period slightly longer than one-half minute, whereupon thereafter the circuit for the motor M is established across the contacts 64 and 66 and automatic operation of the selector valve may then take place.

Another advantage in using the switch S' responsive to oil pressure is that the circuit of the selector valve operating mechanism is broken

whenever the engine is stopped and the oil pressure accordingly recedes. This is true regardless of whether or not the ignition switch 55 is in the "off" or "on" position. Accordingly, neglect to turn off the ignition switch does not permit the selector valve operating mechanism to continue its cycles of operation, thus running the battery down, since the circuit would be opened across the contacts 64 and 66. The signal light 113 is so associated with the selector valve operating mechanism that in the event the ignition switch is left on, when the fuel pressure in the bellows chamber 34 of the switch S recedes, after the engine stops, the switch will be closed as in Figure 2, thus energizing the bulb and indicating to the pilot that his ignition switch is still on.

From the foregoing description of the operation of my fuel system, it is obvious that the selector valve is automatically operated only at the times desired, as when one fuel tank becomes empty and it is desirable to secure fuel from another tank. The switch S, responsive to fuel pressure, initiates operation of the selector valve mechanism and the switch 84-85 terminates such operation at the completion of a selector valve movement. The undesirable result of continued repetition of the cycles of operation of the selector valve experienced when the ignition switch 55 is accidentally left on after the engine is stopped, and as caused by reduction of fuel pressure in the switch S, causing it to close, is eliminated by the use of my safety switch S' which is normally in the open position and closes only after the oil pressure in the engine has risen towards its normal operating pressure.

Any time that the operator wishes to test the indicator light 113 he may do so by manually closing the switch 116, thus providing a circuit for the indicator light direct from the battery 54 through 55, 56, 58, 17, 113, and 115 to ground. He is thus assured that current supply to automatically operate the selector valve is available and that his indicator bulb is not burned out, so that any subsequent fuel failure occurring as a result of fuel tanks becoming empty will be indicated to him by flashing on of the bulb under control of the switch S. As soon as the selector valve operation has been completed, then the light will be extinguished, due to opening of the switch S. During selector valve operation, the pointer 120 cooperates with the dial 121 to indicate what tanks are being connected to the pump 13 and which are empty and passed up by the automatic selector valve operation.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention and desire to secure by Letters Patent of the United States:

1. In an automatic fuel system having an automatic safety switch, a selector valve connected between a plurality of fuel tanks and an internal combustion engine having a pressure oiling system, a motor for operating said selector valve at high speed when changing from one selector valve position to the next, a fuel pressure and selector valve position responsive switch controlling energization of said motor, a shunt switch in circuit with said motor, a resistance shunting said shunt switch, said shunt switch being opened by said selector valve when adjacent port registering position whereby to slow down the rotation of said selector valve, and an oil pressure responsive switch in series with said fuel pressure and selector valve position responsive switch and operable to establish a circuit thereto only when said internal combustion engine is operating and delivering oil in excess of a predetermined pressure to said pressure oiling system.
2. In an automatic fuel system having an automatic safety switch, a selector valve connected between a plurality of fuel tanks and an engine having a pressure oiling system, a motor for operating said selector valve from one selector valve position to the next, a fuel pressure and selector valve position responsive switch controlling energization of said motor, and an oil pressure responsive switch in series with said fuel pressure and selector valve position responsive switch and operable to establish a circuit thereto only when said engine is operating and delivering oil in excess of a predetermined pressure to said pressure oiling system.
3. An automatic fuel system comprising a selector valve connected between a plurality of fuel tanks and an internal combustion engine, a motor for operating said selector valve when changing from one selector valve position to the next, a fuel pressure and selector valve position responsive switch controlling energization of said motor, and an automatic safety switch in series with said fuel pressure and selector valve position responsive switch and operable to establish a circuit thereto in response to a running condition of said internal combustion engine immediately following the starting thereof.
4. An automatic fuel system comprising a selector valve for selectively connecting any one of a plurality of fuel tanks with a fuel pump operable to pump fuel to an engine having a pressure oiling system, a motor for quickly operating said selector valve from one selector valve position to the next, means under control of said selector valve to slow down said motor adjacent port alignment position of said selector valve, a fuel pressure and selector valve position responsive switch for controlling energization of said motor, an electrically operated clutch connection between said motor and said selector valve, said clutch connection being energizable by said fuel pressure and selector valve position responsive switch, and an automatic oil pressure responsive safety switch in series circuit with said fuel pressure and selector valve position responsive switch, said last switch being opened by reduction of oil pressure in said oiling system below a predetermined degree and closed by increase of oil pressure above said predetermined degree.
5. In an automatic fuel system having an automatic safety switch, a selector valve for selectively connecting any one of a plurality of fuel tanks with a fuel pump operable to pump fuel to an internal combustion engine having a pressure oiling system, a motor for operating said selector valve from one selector valve position to the next, a fuel pressure and selector valve position responsive switch for controlling energization of said motor, an electrically operated clutch connection between said motor and said selector valve, said clutch connection being energizable by said fuel pressure and selector valve position responsive switch, and an oil pressure responsive switch in series circuit with said fuel pressure and selector valve position responsive switch, said oil pressure responsive switch being

opened by reduction of oil pressure in said oiling system below a predetermined degree and closed by increase of oil pressure above said predetermined degree.

6. In an automatic fuel system of the class described having an automatic safety switch, a selector valve for selectively connecting any one of a plurality of fuel tanks with a fuel pump operable to pump fuel to an engine having a pressure oiling system, a motor for operating said selector valve from one selector valve position to the next, a fuel pressure and selector valve position responsive switch for controlling energization of said motor, and an oil pressure responsive switch in series circuit with said fuel pressure and selector valve position responsive switch, said oil pressure responsive switch being opened by reduction of oil pressure in said oiling system below a predetermined degree and closed by increase of oil pressure above said predetermined degree.

7. In an automatic fuel system having an automatic safety switch, a selector valve for selectively connecting any one of a plurality of fuel tanks with a fuel pump operable to pump fuel to an engine having a pressure oiling system, a motor for operating said selector valve when changing from one selector valve position to the next, a fuel pressure responsive switch and an oil pressure responsive switch in series circuit for controlling said motor, said oil pressure responsive switch being hydraulically connected with said oiling system of said engine and being set to normally remain open and to close only upon oil pressure in said oiling system attaining an operating pressure condition, said fuel pressure responsive switch being closed by a drop of fuel pressure and carried in closed position to another position upon subsequent rise of fuel pressure, and means operable in synchronism with the movement of said selector valve for opening said fuel pressure responsive switch when in said another position.

8. In an automatic fuel system having an automatic safety switch, a selector valve for selectively connecting any one of a plurality of fuel tanks with a fuel pump operable to pump fuel to an engine having a pressure oiling system, a motor for operating said selector valve at relatively high speed when changing from one selector valve position to the next, a fuel pressure responsive switch and an oil pressure responsive switch in series circuit for controlling energization of said motor, said oil pressure responsive switch being hydraulically connected with said oiling system of said engine and being set to normally remain open and to close only upon oil pressure in said oiling system attaining an operating pressure condition, said fuel pressure responsive switch being closed by a drop of fuel pressure and moved to another position but retained closed upon subsequent rise of fuel pressure, means operable in synchronism with the movement of said selector valve for opening said fuel pressure responsive switch when in said another position, and means for slowing down the operation of said motor when said selector valve has progressed to a position adjacent alignment of its ports.

9. An automatic fuel system having an automatic safety switch comprising a selector valve for selectively connecting any one of a plurality of fuel tanks with a fuel pump operable to pump fuel to an engine having a pressure oiling system, means for operating said selector valve from one

selector valve position to the next, a fuel pressure responsive switch and an oil pressure responsive switch for energizing said selector valve operating means, said oil pressure responsive switch being hydraulically connected with said oiling system of said engine and being set to normally deenergize said pressure responsive switch when oil pressure in said oiling system is below an operating pressure condition, said fuel pressure responsive switch being closed by a drop of fuel pressure and moved while closed to another position upon subsequent rise of fuel pressure, and means operable in synchronism with the movement of said selector valve for opening said fuel pressure responsive switch when in said another position.

10. An automatic fuel system comprising a selector valve for connection between a plurality of fuel tanks and a fuel pump operable to pump fuel from said tanks to an engine having a pressure oiling system, means for changing said selector valve from one selector valve position to the next, a fuel pressure responsive control device and an oil pressure responsive control device interconnected with each other and with said means to operate the means and to stop operation thereof, said oil pressure responsive control device being normally in position to not operate said means and upon build-up of oil pressure assuming a position to operate said means, and said fuel pressure responsive control device being normally in position to not operate said means and upon failure of fuel pressure assuming a position to effect operation of said means to move said selector valve in response to fuel pressure after the oil pressure of the engine has been built up and to prevent such operation of said means and movement of said selector valve before such build-up of oil pressure.

40 11. An automatic fuel system comprising a selector valve for connection between a plurality of fuel tanks and a fuel pump operable to pump fuel from said tanks to an engine having a pressure oiling system, electrically operated means for changing said selector valve from one selector valve position to the next, a fuel pressure and selector valve position responsive switch and an oil pressure responsive switch connected in series with each other and with said electrically operated means to control energization of said electrically operated means, said oil pressure responsive switch being normally in open position and upon build-up of oil pressure assuming closed position, and said fuel pressure responsive switch being normally in open position and upon failure of fuel pressure assuming closed position to effect energization of said electrically operated means to change said selector valve from one selector valve position to the next in response to fuel pressure after the oil pressure of the engine has been built up and to prevent such operation of said electrically operated means and change of position of said selector valve before such build-up of oil pressure.

65 12. In an automatic fuel system, a selector valve connected between a plurality of fuel tanks and an engine using fuel therefrom, said engine having a pressure oiling system, automatic means for changing said selector valve from one selector valve position to the next, a fuel pressure and selector valve position responsive switch and an oil pressure responsive switch connected in series with each other and with said automatic means to control its energization, said oil pressure responsive switch being normally in an open posi-

tion and upon build-up of oil pressure assuming closed position, and said fuel pressure responsive switch being normally in open position and upon failure of fuel pressure assuming closed position whereby said automatic means is energized in response to fuel pressure only after the oil pressure of the engine has been built up.

13. In an automatic fuel system having an automatic safety switch, a selector valve connected between a plurality of fuel tanks and an internal combustion engine having a pressure oiling system, a motor for operating said selector valve when changing from one selector valve position to the next, a fuel pressure and selector valve position responsive switch and an oil pressure responsive switch both in series with said motor whereby they are operable to establish a circuit thereto only when the fuel pressure is low and said internal combustion engine is operating and delivering oil in excess of a predetermined pressure to said pressure oiling system, a signal light to indicate the operation of said motor whenever said oil pressure responsive switch is closed, said signal light being connected in series with said fuel pressure and selector valve position responsive switch only and thereby energized when said fuel pressure responsive switch responds to fuel pressure failure regardless of the position of said oil pressure responsive switch.

14. In an automatic fuel system having an automatic safety switch, a selector valve connected between a plurality of fuel tanks and an engine having a pressure oiling system, a motor for operating said selector valve from one selector valve position to the next, a fuel pressure and selector valve position responsive switch controlling said motor and an oil pressure responsive switch in series with said fuel pressure and selector valve position responsive switch and operable to establish a circuit thereto only when said engine is operating and delivering oil in excess of a predetermined pressure to said pressure oiling system, said oil pressure responsive switch being manually operable independent of said pressure oiling system.

15. An automatic fuel system having an automatic safety switch and comprising a selector valve connected between a plurality of fuel tanks and an engine having a pressure oiling system, means for operating said selector valve from one selector valve position to the next, a fuel pressure and selector valve position responsive switch controlling energization of said means, an oil pressure responsive switch in series with said fuel pressure responsive switch and both operable to establish a circuit to said motor when said engine is delivering oil in excess of a predetermined pressure to said pressure oiling system and the fuel pressure is low, a signal light to indicate the operation of said means whenever said oil pressure responsive switch is closed, said signal light being connected for operation by said fuel selector valve position responsive switch independent of said oil pressure responsive switch, and said oil pressure responsive switch being manually operable independent of the pressure in said pressure oiling system to permit testing of the fuel system when desired and returning to position permitting normal functioning of said means by a subsequent rise in oil pressure of said oiling system.

16. In an automatic fuel system, an engine, a

selector valve for selectively connecting one of a plurality of fuel tanks with said engine, means for operating said selector valve from one selector valve position to the next, a signal light to indicate the operation of said means, a fuel pressure and selector valve position responsive device controlling energization of said means and signal light, a device responsive to engine operation, connected with said fuel pressure and selector valve position responsive device and operable in conjunction therewith to render said means operable only when said engine is operating, said device responsive to engine operation being manually operable independent of engine operation to permit testing of the fuel system when desired.

17. An automatic fuel system having an automatic safety switch and comprising a selector valve connected between a plurality of fuel tanks and an engine having a pressure oiling system, means for operating said selector valve from one selector valve position to the next, a fuel pressure and selector valve position switch, an oil pressure responsive switch in series with said fuel pressure and selector valve position responsive switch and both operable to establish a circuit to said means for operating said selector valve when said engine is delivering oil in excess of a predetermined pressure to said pressure oiling system and the fuel pressure is low, and a signal light to indicate the operation of said means, said signal light being connected for operation by the closure of said fuel pressure and selector valve position responsive switch.

18. In an automatic fuel system, an engine, a selector valve for selectively connecting one of a plurality of fuel tanks with said engine, means for operating said selector valve from one selector valve position to the next, a signal light to indicate the operation of said means, a fuel pressure and selector valve position responsive device controlling said means and signal light, a device having a dormant position when the engine is idle and another position when the engine is running, said last device being connected with said fuel pressure and selector valve position responsive device and operable in conjunction therewith to render said means operable only when said fuel pressure and selector valve position responsive device is in low fuel pressure position and when said last device is in said another position, said signal light being controlled by said fuel pressure and selector valve position responsive device only and thereby operable only in response to fuel pressure failure and independent of engine operation.

19. An automatic fuel system comprising a selector valve connected between a plurality of fuel tanks and an internal combustion engine having means for producing pressure when the engine is running, means for operating said selector valve to change the selector valve from one position to the next, and a pressure operated safety switch controlling energization of said means, said safety switch being operable to establish a circuit to said means in response to pressure and being manually operable to off position independent of the pressure, said safety switch upon being so manually operated, returning to on position by the build up of such pressure in response to a running condition of the internal combustion engine.

DAVID SAMIRAN.
